BALL PROJECTING MACHINE

Thomas R. Foster and Edward J. Foster,
Baltimore, Md.

Application December 15, 1947, Serial No. 791,836

2 Claims. (Cl. 124—11)

1

This invention refers to pneumatic devices and more particularly to an apparatus for projecting baseballs and the like in such a manner as to be useful for batting practice or throwing a ball or other object either at a target or other objects located at a distant point, the invention having reference more particularly to a machine whereby a ball may be ejected from the device by means of compressed air or other gases and the ball caused to follow a curved course either in a right or left hand direction as well as straight. All of the directions being controlled by the operator of the device.

The conventional types of ball throwing machines are made for throwing a ball in a straight line, and some attempts have been made to produce a machine that would eject the ball in a manner that presented the simulation of a curving ball, but both of these devices have been arranged in separate units and were unsuccessful in their operation. In both instances the batter or catcher knew beforehand the type of ball to be thrown him based on which machine was used to throw the ball, one being set for straight ball throwing and the other for curves, this eliminated the "doubt" from his mind which is necessary for good batting practice.

It is an object of this invention to provide an improved ball-projecting device of the above named character that will be so constructed that it may be moved from place to place for exhibition and practice purposes, and which may be used for projecting or throwing various kinds of objects, especially those called "baseballs" in a manner which may be caught or batted by a person within the range of the projected ball.

It is an object of this invention to provide an improved ball-projecting device of the class described that shall be capable of rotating a ball and causing it to follow a curved course either to the right or left, or upward or downward or in a straight line, as may be desired by the operator, and permit the operator to easily change the course for each succeeding ball thrown in order to compel the one attempting to "bat" or to catch the ball to be constantly on the alert.

It is a further object of this invention to provide an improved ball-projecting device in which the operator can "slow-up" or "speed-up" the delivery speed of the ball to the batter or catcher.

It is an additional object of this invention to provide an improved ball-projecting device in which the speed and type of delivery can be controlled by the operator of the ball-projector.

Other objects will become apparent as the invention is more fully set forth.

Referring to the appended drawings:

Figure 1 is a side elevation of a pneumatic device for ejecting baseballs and the like embodying this invention;

2

Figure 2 is a plan view of Figure 1;

Figure 3 is a sectional view taken along line 3—3 of Figure 1;

Figure 4 is a sectional view taken along line 4—4 of Figure 1;

Figure 5 is an enlarged plan view of a part of the barrel and nose piece showing the control mechanism;

Figure 6 is a sectional view taken along line 6—6 of Figure 5;

Figure 7 is a sectional view taken along line 7—7 of Figure 5;

Figure 8 is a sectional view similar to Figure 6 but in open position;

Figure 9 is a sectional view taken along line 9—9 of Figure 5;

Figure 10 is a view looking in the direction of arrows 10—10 of Figure 5;

Figure 11 is a sectional view taken along line 11—11 of Figure 1, and

Figure 12 is a sectional view taken along line 12—12 of Figure 2, showing the quick operating valve.

Similar reference characters refer to similar parts throughout the drawings.

The ball projecting device indicated in the drawings consists of a tripod 15 having a front leg 16 and provided with collar 17 to limit its penetration into the ground 18, and rear legs 19 having wheels 20 attached at their lower ends for rolling the device along the ground during movement from one place to the other. The rear legs are held in spaced relationship by a bracket 21. A shelf 22 is positioned at the upper ends of the legs to hold them in spaced relationship to each other and also to form a support for a turntable arrangement 23 positioned thereon. The turntable 23 is adjustably rotated on the shelf 22 and held in fixed relationship thereto by an adjustment screw 24, which is threaded into the shelf 22 and slides in slot 25 provided in the turntable 23. A yoke 26 provided on a supporting shaft 27 projects through the shelf 22 and turntable 23 and is adjusted as to height therein by a set collar 28. The upper end of the yoke pivotally supports the pneumatic gun 29. The gun comprises an accumulator 30 for collecting and holding the compressed gases received from the gas tank 31 through a flexible hose 34. The gas tank is positioned on the shelf 32 attached to the front and rear legs and is provided with the customary pressure regulating and control valves 33.

The gun is retained in various raised, lowered and horizontal positions through an arcuate arm 35 attached at one end to the accumulator 30 and having an arcuate slot 36 at its lower end for engagement with a fitting attached to the lower end of the supporting shaft 27 and is fixedly attached thereto by an adjustment screw. The

gun 29 is provided with a barrel 37 to which is attached a nose 38 which controls the action of the ball as it leaves the gun barrel 37. The ball is fed into the barrel through a hole 39 therein when the hole 40 in the sleeve 41 is aligned therewith for feeding the ball into the barrel 37. The nose 38 comprises a collar 42 which is screwed onto the end of the barrel 37. The collar 42 is provided with a bracket 43 to which are pivoted the upper and lower nose sections 44 and 45 that support fingers 46 and 47 respectively. The fingers 47 are provided with resilient covers 48 that create a drag on the ball on two sides while it glides unencumbered along the uncovered finger 46. This mechanism outlined causes the ball to rotate and curve after it leaves the barrel nose. The ball will curve either to the right or left depending on the location of the covered fingers. If the covered fingers are positioned on the right hand side, the ball will curve to the right, if the covered fingers are turned towards the left, the ball will curve towards the left, and up or down. The nose 38 is rotated on the screw-threaded portion of the barrel 37 to change the direction of the curve. The amount of curve administered to the ball is controlled by the adjustment screws 49 and 50. The fingers are thrown out of engagement with the ball during its passage by releasing the thumb nut 51 positioned on bolt 54 through the pressure of springs 52 which move outwardly from the support 53 to contact ears 55 and 56 attached to the upper and lower nose sections 44 and 45. The fingers are covered by shells 57 and 58 respectively, to protect them from contact on their outer surfaces. The barrel 37 is connected to the accumulator 30 by a pipe member 59 in which is inserted a quick acting valve 60. The valve 60 may be of any of the conventional types of quick opening valves now on the market or it may be constructed along the lines shown in Figure 12, in which the body 61 is provided with a hole 62 which is closed by a plate 63 when moved to closing position by the handle 64.

In the operation of the device the pressure regulating valves are set to the predetermined pressure desired, and the control valve opened. This allows the compressed air or gas to pass up through the flexible hose 36 into the accumulator 30 and then to the valve 60.

The adjustment screws 49 and 50 are set against the fingers 46 and 47 to adjust them sufficiently to produce the amount of curve to be used. The nose is rotated on the barrel threads so the covered fingers 47 will be positioned in alignment with the direction the ball is to be curved to, and the nose sections 44 and 45 are locked in position by bolt 54 through the action of thumb nut 51 attached thereto. The sleeve 41 is positioned so the hole 40 in the sleeve aligns with the hole 39 in the barrel 37 and the ball is dropped into the barrel and the sleeve 41 again rotated to close the openings. The barrel is pointed through its rotation in a horizontal manner and aimed at the target, catcher or batter by the screw 24. The gun is pointed up or down on the yoke 26 and may be locked in position by a nut. When it is desired to throw a ball in a straight line the nose sections 44 and 45 are released through the action of the thumb nut 51, 70

which allows the fingers 46 and 47 to move out of engagement with the ball as it passes from the end of the barrel. The speed of the thrown ball may be varied by increasing or decreasing the amount of air or gas used to operate the projector.

While but one general form of the invention is shown in the drawings and described in the specifications, it is not desired to limit this application for patent to this particular form, as it is appreciated that other forms of construction could be made that would use the same principles and come within the scope of the appended claims.

Having thus described the invention, what is claimed is:

1. A ball projecting device comprising a support, a gun barrel mounted on said support, means for supplying compressed gases to said barrel, said gun barrel being rotatably mounted about a transverse axis, pivot means for swinging said gun barrel in a vertical plane, said barrel having an opening in the wall thereof for feeding balls thereinto, means for closing said opening, a nose piece at the end of said barrel, said nose piece supporting a plurality of circularly spaced-apart fingers to contact the ball as it is ejected from said barrel to cause it to curve in a predetermined manner and said nose piece comprising a pair of arcuate members, means for pivoting said members with respect to each other, each of said members having a perforated ear integral therewith, a bolt passing through said ear and having a nut on the free end thereof, spring means between said ears, whereby said nose piece members are yieldingly adjustable with respect to each other, certain of said fingers having a smooth surface and others having their outer portions covered with friction-creating means between said portions and the ball to slow up the travel of the ball at the point of contact while the opposite portion of the ball glides along the smooth surface finger, said nose piece being thus formed into separate units, means for selectively clamping said units on said barrel in a plurality of positions to vary the location of the fingers carried by said nose piece and their contact points with the ball, and means for adjusting the position of said fingers within said nose piece.

2. A ball projecting device as set forth in claim 1, said support including a tripod, rollers at the end of two of the legs thereof and a ground-engaging point at the end of the third leg thereof.
